UNITED STATES PATENT OFFICE.

THOMAS B. JEFFERY, OF CHICAGO, ILLINOIS.

OILING-CAN.

SPECIFICATION forming part of Letters Patent No. 358,932, dated March 8, 1887.

Application filed July 10, 1886. Serial No. 207,645. (No model.)

To all whom it may concern:

Be it known that I, THOMAS B. JEFFERY, a citizen of the United States, residing at Chicago, in the county of Cook and State of Illinois, have invented certain new and useful Improvements in Oiling-Cans, which are fully set forth in the following specification, reference being had to the accompanying drawings, forming a part thereof.

10 The purpose of my invention is to provide improved means for automatically closing the discharge-nozzles of machinery-oiling cans when the same are not in use; and it is especially designed to be applied to small oilers—15 such as are adapted to be carried in the pocket, and which for that purpose are made flat, as in the form of hollow disks with elastic sides, to which the pressure is applied to discharge the oil.

20 My invention consists of an interior valve closing the discharge-nozzle and having its stem suitably connected to the elastic sides of the can, so that the compression of the can, which tends to discharge the oil, opens the 25 valve to allow the oil to escape.

In the drawings, Figure 1 is an elevation of an oiling-can with one side broken away, showing the valve-actuating mechanism. Fig. 2 is a transverse vertical section through the can, 30 showing the valve and its actuating mechanism in elevation. Fig. 3 is an elevation of a slightly-modified form of the valve-actuating mechanism.

A' and A² are the opposite elastic sides of 35 the can.

B is the nozzle; C, a valve which closes it interiorly; C', the valve-stem; A¹⁰, a bracket secured to the inner face of the side A', affording a bearing to the lower end of the valve-40 stem C'.

A¹¹ is a bracket secured to the face A' at about the center thereof.

D is a lever pivoted on the bracket A¹¹ and connected at one end to the valve-stem C'.

45 A²⁰ is a bracket secured to the inner face of the side A² of the can and extended transversely past the arm D² of the lever D, and having the abutment or lateral stud a²⁰, which engages the said arm D². It may have, also, 50 the further stud a²¹, engaging the arm D² on the opposite side.

The normal position of the parts thus far de-

scribed is as shown in full lines in Fig. 2, the valve C being seated in the nozzle. By the compression of the sides A' and A², or either 55 of them, the bracket A²⁰ is moved toward the bracket A¹¹, and the stud a²⁰, engaging the arm D² of the lever D, rocks it over its pivot on the bracket A¹¹, causing the end of the arm D' to move downward and carry the valve-stem 60 C' toward the bottom of the can, sliding it in the bracket A¹⁰, and withdraw the valve C from its seat in the nozzle. When the pressure is removed from the sides A' A², their reaction reverses the movement of the parts, and 65 the stud a²¹, engaging behind the arm D², rocks it in the opposite direction from that first described, causing it to seat the valve in the nozzle.

In order to avoid the danger of imperfectly 70 seating the valve when the sides A' and A² become, by continued use, permanently bent inward, so that they do not react to the full distance necessary to seat the valve closely, I 75 provide the spring E, coiled about the lower portion of the valve-stem C' and stopped between the bracket A¹⁰ and a shoulder, C¹⁰, on the valve-stem. This spring tends to throw the valve-stem upward, and will seat it regardless of the reaction of the sides. 80

The form shown in Fig. 3 differs from that shown in the other figures only in appearance, not in essential action. The lever D in both forms operates substantially as a bell-crank lever, the fulcrum being on the bracket A¹⁰, 85 power being applied by the stud a²⁰, and the resistance or weight being the valve-stem connected to the end of the arm D'. In the second form, Fig. 3, the stud a²⁰ performs the functions of both the studs a²⁰ and a²¹ in the 90 first form, the slot d² in the arm D² of the lever D, in which said stud a²⁰ engages, enabling it to move the lever both ways.

I claim—

1. In combination with the nozzle and the 95 elastic lateral walls of the can, a valve closing the nozzle interiorly, having its stem extended between the elastic walls, a bell-crank lever pivoted upon one of the elastic walls, having one end connected to the valve-stem and the other end extended on the opposite side of the fulcrum from the nozzle and engaged by a projection from the opposite wall, substantially as set forth.

2. In combination with the oiling-can having an elastic side, a valve closing the nozzle and having its stem extended substantially parallel to that side, a lever pivoted on the 5 interior wall of the can connected to the stem, and a projection, as the bracket A²⁰, connected to the elastic side and engaging the lever, substantially as and for the purpose set forth.
3. In combination with the oiler having opposite elastic sides, and the valve-stem extending between them, a lever connected to the stem, pivoted on one of the sides and actuated by a projection from the other, substantially as set forth.
- 15 4. In combination with the oiling-can having the elastic sides A' and A², provided, re-

spectively, with the brackets A¹¹ and A²⁰, the valve-stem C' and its bearing-bracket A¹⁰, the bell-crank lever D, pivoted on the bracket A¹¹, and connected to the valve-stem and engaged by the bracket A²⁰, and the spring E, engaging the stem C and stopped against the bracket A¹⁰, intending to seat the valve, substantially as set forth. 20

In testimony whereof I have hereunto set 25 my hand, this 6th day of July, A. D. 1886, in the presence of two witnesses, at Chicago, Illinois.

THOS. B. JEFFERY.
